UNITED STATES PATENT OFFICE.

CHARLES OSBORNE, OF NORTH ATTLEBOROUGH, MASS., ASSIGNOR TO THE WHITING MANUFACTURING COMPANY, OF NEW YORK CITY.

DESIGN FOR HANDLES OF SPOONS AND FORKS.

Specification forming part of Design No. 7,808, dated October 27, 1874; application filed June 20, 1874.
[Term of Patent 14 years.]

CASE B.

To all whom it may concern:

Be it known that I, CHARLES OSBORNE, of North Attleborough, Bristol county, Massachusetts, have invented a new and original Design for the Handles of Spoons and Forks, of which the following is a specification:

The accompanying drawings form a part of this specification.

Figure 1 is a view of the upper side or front of the handle, and Fig. 2 a view of the under or reverse side.

Similar letters of reference indicate corresponding parts.

The handle is composed, as usual, of two principal sections—finger-piece A and shank B. The finger-piece is of an elongated double tapering form, with a bead, *a*, around the edge, the field within which is decorated with gracefully-curved stems *b*, bearing branched or lobed leaves *d* and pendent flowers *e* of the honeysuckle sort, and corresponding buds or undeveloped flowers *f*. The stem is grooved or formed with a series of nearly-parallel beads, *g*. The handle is inclosed, near the junction of the shank and finger-piece, by corded crossed bands *i j*, and near the lower end of the shank,

or its junction with the body of the spoon or fork, with a corresponding band, *k*.

The pattern or design may be varied in size and in the precise arrangement of the stems and other details, so long as they form essentially the same design, and produce the same ornamental and distinctive effect.

I claim as my invention in designs for spoon and fork handles—

1. The finger-piece A, with the honeysuckles *e f*, leaves *d*, and stems *b*, and with the bead *a* on the finger-piece A, as shown and described.

2. The shank B, with the beads *g* and crossed bands *i j*, and band *k*, as shown and described.

3. The within-described design of a spoon or fork handle, composed of a finger-piece, A, and shank B, both distinctively formed and ornamented, as shown and described.

In testimony whereof I have hereunto set my hand this 18th day of June, 1874, in the presence of two subscribing witnesses.

CHARLES OSBORNE.
